UNITED STATES PATENT OFFICE.

CHARLES B. ULRICH, OF WAUSAU, WISCONSIN.

DRAFTING-BOARD.

1,147,908.

Specification of Letters Patent. Patented July 27, 1915.

Application filed August 28, 1912. Serial No. 717,420.

To all whom it may concern:

Be it known that I, CHARLES B. ULRICH, a citizen of the United States, residing at Wausau, in the county of Marathon and State of Wisconsin, have invented certain new and useful Improvements in Drafting-Boards, of which the following is a full, clear, concise, and exact description, reference being had to the accompanying drawings, forming a part of this specification.

My invention relates to an improved construction of drafting board so made that the board may be changed in size either so as to accommodate drawings of different size or so that one portion of the board may be used in making the drawings while the adjustable extension may be used for holding reference papers.

My invention has particularly for its object the construction of a drafting board of the kind referred to in such a manner that the board proper will afford a smooth even surface for receiving the drawings, and that the board can be readily kept in flat condition.

By my construction I further provide an effective condition of the board for receiving the tacks commonly employed to hold the drawings in place upon the board.

In addition to the results just referred to, I also secure the very desirable result by my invention of having a sliding extension mounted within the body of the drafting board itself so that the whole construction is very compact and that the extension, when drawn out from the end of the board a desired amount, affords a nearly continuous surface without, however, interfering in any way with securely holding successive portions of the width of the drafting table by means of retaining cleats, so that the drafting board is kept flat at all times.

In making the drafting board, I preferably place the grain of the wood used in building up the board so that the strength of the structure is not decreased materially, by mounting the sliding extension in the board itself. To secure this result, I build up the drafting board proper out of strips of soft wood so taken that the edge grain, as distinguished from the leaf grain, is presented to the top and bottom of the drafting board. This results in giving added strength to the parts of the drafting board which project through the sliding extension to engage the retaining cleats and also af-

fords a better engagement for the tacks used to hold the paper in place on the board since the edge grain tends to close up when the tacks are withdrawn, and thus it not only follows that the holes formed in the board by the tacks are closed in a large measure, but that the tacks are more firmly held by the board when they are in place.

In connection with the drafting board above described, I preferably employ an adjustable trestle by which the height of the board may be regulated to suit the user or, if desired, the trestle may be folded up and the board and trestle may be stored away in a minimum amount of room when not in use. When the board is in use, the sliding extension gives practically twice the capacity to a drafting table which the drafting board without the extension would have and thus the tables may be placed more closely together in a drafting room than would be the case if it were necessary to leave a passageway around the tables equal in length to the extended length of my improved board.

It will be understood that while I have shown a folding trestle to support my improved drafting board, that other devices as desired may be employed for this purpose and that regardless of how the board is supported, the sliding extension serves the purposes described above.

The adjustable trestle shown and described herein is provided with a foot-rest which automatically adjusts itself to the feet of the user regardless of the adjustment of the trestle.

The several drawings illustrating my invention are as follows:

Figure 1 shows in plan view my improved drafting board with the sliding extension pulled out; Fig. 2 is a front elevation of the drafting board shown in Fig. 1 with the adjustable trestle for supporting the board; Fig. 3 is an enlarged cross-sectional view of the drafting board taken along the line 3—3 in Fig. 1; and Fig. 4 shows in reduced end view the adjustable trestle shown in Fig. 2.

Similar numerals refer to similar parts throughout the several views.

As shown in Fig. 1, the drafting board consists of a plurality of strips 1 of soft wood, between and to which intermediate strips 2 are glued to form a drafting surface, as indicated in Fig. 1. As shown in Fig. 3 the strips 1 are considerably deeper than the

strips 2 and have formed in their side walls near the surface of the drafting board V-shaped grooves for receiving similarly formed tongues formed on the sides of the 5 strips 2. As a result of this construction, when the strips 1 and 2 are glued together there is no chance for them to be displaced vertically relatively to each other and they are securely held in the position indicated 10 owing to the increased surface between them. Just below the bottom of the strips 2, grooves are formed in the side walls of the strips 1 to receive tongues extending side-wise from the strips 3 which constitute 15 the sliding extension of the drafting table. The combined depth of the strips 2 and 3 is not as great as the depth of the strips 1 and through the portions of the strips 1 projecting below the strips 3 transverse dove- 20 tail grooves are formed to receive tapered tongues of similar conformation formed on the upper edges of the retaining cleats 4 and 5 by means of which the drafting board is held flat. The dove-tail grooves formed in 25 the pieces 1 are also tapered to fit the taper tongues on the cleats so that by driving the cleats 4 and 5 tightly into the dove-tail grooves, they may properly hold the drafting board in flat position at all times.

30 The strips 3 have end tongues or tenons formed on their right hand ends which enter a corresponding groove in a head-piece 6. These pieces 3 are held together at their right hand end as shown in Figs. 1 and 2.

35 The left hand ends of one or more of the strips 3 have secured to their under side a stop cleat for engaging the retaining cleat 4 when the extension is pulled out, so that it can not be entirely removed from the drafting board.

40 In making the pieces 1 and 2, they are cut from the lumber employed (which may be of any soft wood, although I find soft pine to answer the purpose admirably) in such a way that the leaf of the grain of the wood extends vertically, or in other words, that the pores are presented to the top and bottom edges of these strips 1 and 2. From this it will appear that the leaves of the 45 wood extend uninterruptedly between the strips 3 from top to bottom in the pieces 1 and thus these pieces afford a much stronger support for the pieces 3 of the sliding extension and also for the retaining 50 cleats 4 and 5 than would be the case were the grain in the pieces 1 not thus placed. By presenting the pores or edge grain of the pieces 1 and 2 to the upper surface of the drafting board, a better engagement is af- 55 fforded for the tacks used to hold the paper on the board than would be afforded by the side or leaf grain of the strips and furthermore the edge grain tends to close when the tacks are withdrawn, thus reducing the 60 holes in the board to a minimum.

The left hand end of the strips 1 and 2 have formed on their ends, end tongues for engaging a corresponding groove in a T-square guide 7, made preferably of hard wood carefully trued up and smoothed to 70 afford an accurate straight edge guide for the T-square head. The strips 1 and 2 are glued to the guide 7 only near its middle, and at either end the guide is secured to the strips by angle irons 8 by means of suitable 75 screws, as indicated in Figs. 1 and 2, and in either one or both legs of each of these angle irons the clearance holes for the screws are sufficiently extended transversely of the angle irons so that the drafting board may 80 shrink or swell without changing the accuracy of the guide 7 and without danger of splitting the drafting board proper.

It will be noted that the upper surfaces of the strips 3 are quite wide relatively to 85 the spaces which are left between them, and thus, since the upper surfaces of such strips lie in the same plane, they together constitute a working surface which is practically uninterrupted and affords a very effective 90 support for reference drawings and papers of any description. If it is desired to make a drawing longer than the drafting board proper, an auxiliary board of suitable size, as shown at 3^a may be placed on the extension to extend and continue the surface of 95 the drafting board proper.

The drafting board proper is supported as shown in the drawings by an adjustable trestle consisting of two diagonally disposed 100 legs 9 and 10 hinged at their upper ends to the cleats 4 and 5. These legs have pivoted to them forwardly extending legs 11 and 12, to the lower ends of which the braces 13 and 14 are pivoted. The upper ends of the 105 braces 13 and 14 are of reduced cross-section to engage desired ones of the holes formed in the under surface of the legs 9 and 10. A corresponding series of holes is formed in the upper surface of the legs 9 110 and 10 to receive the lower ends of the braces 15, which are pivoted at their upper ends to the rear ends of the retaining cleats 4 and 5. In the drawings, the brace 15 secured to the cleat 5 is the only one which 115 appears since the other one is hidden behind the other parts both in Figs. 2 and 4.

The braces 15 are secured rigidly together near their lower ends by a cross-piece 16 so that by adjusting one of them, the other one 120 is correspondingly adjusted and the braces 13 and 14 are similarly secured together by a cross-piece 17 for the same purpose. This cross-piece 17 serves as a foot rail when desired. The legs 11 and 12 have supported 125 between them a foot rest 18 which extends the length of the drafting board and this foot-rest is freely pivoted at each end so that it may turn and accommodate itself to the feet of the user, thus at once doing away 130

with the annoyance which would otherwise be experienced in connection with an adjustable trestle support, of having the feet rest upon the edge of the foot rest for certain 5 positions and upon the flat surface of the foot-rest for other positions of the trestle. It is generally unnecessary in using the extension to the drafting board to support its outer end since the weight required to be 10 supported is usually small and it is generally not necessary to draw the extension out its full length. For those cases, however, in which it is desirable to support relatively heavy weights by the extension 15 and to draw it out its full length, I provide a removable support consisting of a leg 19 similar to the leg 9 pivoted to a cross piece 20 having dowel pins 21 secured therein to removably engage corresponding holes in 20 the underside of the head piece 6. The leg 19 has pivoted thereto a leg 22 similar to the leg 11 and these legs are secured in the desired position relatively to the cross-piece 20 by means of braces 23 and 24 in the 25 same manner that the legs 9 and 11 are held in position by the braces 13 and 15. Of these braces 23 and 24, the brace 23 alone is seen since the brace 24 is located behind the leg 19 and hidden thereby. The leg 19 is 30 braced to the leg 10 by means of a cross-piece 25 which carries a plurality of dowel pins for engaging holes in the edges of the legs 19 and 10 so as to hold the leg 19 securely against lateral displacement in any 35 desired position depending upon the extent to which the extension has been drawn out.

From the above description it will appear that the depth of my improved drafting board construction is but slightly greater 40 than that usually employed, and furthermore since the pieces 2 are of comparatively small depth, the amount of strain exerted upon the board by the retaining cleats 4 and 5 when the latter are properly in place 45 to hold the board flat is reduced to a minimum.

A drawer 27 is preferably mounted on the underside of the drafting table, this drawer being shallow so as to not unnecessarily take 50 up the clearance left under the drafting board, for as is well known to users of these devices, it is very desirable that ample clearance space be left under the drafting board for the knees of the draftsmen since 55 the board must be used frequently when the draftsmen are in a sitting position. In order that the drawer 27 may be quite shallow and yet afford a sufficient receptacle for drafting instruments, pencils, etc., I provide a separate tray 28 for holding the ink 60 bottles, said tray being secured to the outer side of the retaining cleat 5.

It is to be understood that while I have 65 shown the sliding strips 3 of the cross-section described above, it is not necessary that

these strips have that particular conformation since the essential thing is that grooves or openings be provided in the body of the drafting board proper to receive the sliding strips without interfering in any way with 70 reinforcing the board laterally so that it may be stiff enough to do the work required of it without danger of splitting, and it is only necessary that the strips 3 have such a cross-section that they are properly supported in the body of the drafting board above its lower surface. In this way, the upper surface of the sliding extension is brought as near as possible to the working surface of the drafting board proper without unduly weakening the drafting board. 75

It will be observed that one of the uses to which the improved drafting board described above may be put is that when for any reason two draftsmen may work at the 80 same board on comparatively small work, one using the drafting board proper in the regular manner, and the other using the extension by means of a suitable filler 3^a, and that the second draftsman may be located on the other side of the drafting board from the first draftsman and use the head piece 6 as a guide for his T-square. 85

While I have shown my invention in the particular embodiments herein shown and described, I do not, however, limit myself to these constructions, but desire to claim any equivalents that will suggest themselves to those skilled in the art. 90

What I claim is:

1. In a drafting board, the combination of alternate strips of wood extending the full depth of the board, intermediate strips extending from the top of the board but a portion of its depth, transverse retaining 100 cleats engaging said alternate strips at a distance below the said intermediate strips, sliding strips in the spaces between said intermediate strips and said retaining cleats, and a head piece for securing the sliding 105 strips together at one end. 110

2. In a drafting board, the combination of a first set of strips of wood extending the full depth of the board, a second set of strips extending from the top of the board but a portion of its depth, transverse retaining cleats engaging said first set of strips at a distance below said second set of strips, sliding strips in the spaces between said second set of strips and said retaining cleats, 115 and a head-piece for securing the sliding strips together at one end, said sliding strips having tongues formed on their edges to engage corresponding grooves formed in the sides of said first set of strips. 120

3. In a drafting board, the combination of alternate strips of wood extending the full depth of the board, intermediate strips extending from the top of the board but a portion of its depth, transverse retaining 125 strips

cleats engaging said alternate strips at a distance below the said intermediate strips, sliding strips in the spaces between said intermediate strips and said retaining cleats, and a head piece for securing the sliding strips together at one end, said alternate strips and said intermediate strips being made wholly or in part so that the leaf grain of the wood extends perpendicularly from the surface of the drafting board.

4. In a drafting table, the combination of a drafting board comprising alternate strips of wood extending the full depth of the board, intermediate strips extending from the top of the board but a portion of its depth, transverse retaining cleats engaging said alternate strips at a distance below the said intermediate strips, sliding strips in the spaces between said intermediate strips and said retaining cleats, a head piece for securing the sliding strips together at one end, a support for the drafting board, and a support for said head piece when extended, said support for the head piece being readily removable therefrom.

5. In a drafting table, the combination of a drafting board comprising alternate strips of wood extending the full depth of the board, intermediate strips extending from the top of the board but a portion of its depth, transverse retaining cleats engaging said alternate strips at a distance below the said intermediate strips, sliding strips in the spaces between said intermediate strips and said retaining cleats, a head piece for securing the sliding strips together at one end, a support for the drafting board, a support for said head piece when extended, and a brace extending from the head piece support to the drafting board support, said brace being readily removable from the head piece support and the drafting board support.

6. In a drafting table, the combination of a drafting board comprising alternate strips of wood extending the full depth of the board, intermediate strips extending from the top of the board but a portion of its depth, transverse retaining cleats engaging said alternate strips at a distance below the said intermediate strips, sliding strips in the spaces between said intermediate

strips and said retaining cleats, a head piece for securing the sliding strips together at one end, a support for the drafting board, a support for said head piece when extended, and a brace extending from the head piece support to the drafting board support, said brace having hooks on its ends for removably engaging said head piece support and said drafting board support.

7. In a drafting board, the combination of a set of strips of wood, another set of strips of wood extending below said first-mentioned strips of wood, retaining cleats engaging some or all of said other strips, and sliding strips in the spaces between said cleats and said first-mentioned strips.

8. In a drafting board, the combination of a set of strips of wood, another set of strips of wood extending below said first-mentioned strips of wood, retaining cleats engaging some or all of said other strips, sliding strips in the spaces between said cleats and said first-mentioned strips, and a removable support for the outer end of said sliding strips.

9. In a drafting board, the combination of two sets of strips of wood secured together to form the working surface of the board, the strips of one of said sets projecting below the under surface of the strips of the other set, and retaining cleats engaging the projecting portions of some or all of said projecting strips.

10. In a drafting board, the combination of two sets of strips of wood secured together to form the working surface of the board, the strips of one of said sets projecting below the under surface of the strips of the other set, and retaining cleats engaging the projecting portions of some or all of said projecting strips, said strips being made wholly or in part so that the leaf grain of the wood extends substantially perpendicularly from the working surface of the drafting board.

In witness whereof, I hereunto subscribe my name this 26th day of August, A. D., 1912.

CHARLES B. ULRICH.
